DESIGN FOR A TOY AUTOMOBILE OR SIMILAR ARTICLE

Stanley V. W. Hiller, Jr., Berkeley, Calif.

Application June 21, 1940, Serial No. 93,161

Term of patent 7 years

To all whom it may concern:

Be it known that I, Stanley V. W. Hiller, Jr., a citizen of the United States, residing in the city of Berkeley, county of Alameda, State of California, have invented a new, original, and ornamental Design for Toy Automobiles or Similar Articles, of which the following is a specification, reference being had to the accompanying drawings, forming part thereof.

Fig. 1 is a side elevation of a toy automobile showing my design;

Fig. 2 is a front elevation thereof;
Fig. 3 is a rear elevation thereof;
Fig. 4 is a top plan view thereof; and
Fig. 5 is a bottom plan view thereof.

I claim:

The ornamental design for a toy automobile or similar article, substantially as shown.

STANLEY V. W. HILLER, JR.
